UNITED STATES PATENT OFFICE.

THOMAS E. MURRAY, JR., AND JOSEPH B. MURRAY, OF BROOKLYN, NEW YORK.

HOLLOW PROJECTILE-SHELL OF SHEET METAL.

1,350,828.

Specification of Letters Patent. Patented Aug. 24, 1920.

Application filed July 15, 1918. Serial No. 244,935.

To all whom it may concern:

Be it known that we, THOMAS E. MURRAY, Jr., and JOSEPH B. MURRAY, citizens of the United States, residing at Brooklyn, in the 5 county of Kings and State of New York, have invented a certain new and useful Improvement in Hollow Projectile-Shells of Sheet Metal, of which the following is a specification.

10 The invention is an elongated hollow projectile shell formed integrally of sheet metal, and a process of making the same, whereby we are enabled to produce such shells with great rapidity, in very large quantities and 15 at a greatly reduced cost as compared with that of shells as at present made. As a matter of record of actual performance, we are now producing shells for the United States Government in elongated ogival pointed 20 form, and of $9\frac{1}{2}$ inches in diameter and 20 inches in length, at the rate of 2000 per day of 24 hours. The actual time of making such a shell from the rectangular blank of sheet metal to the completed article is less 25 than one minute, including the time of handling and transportation to the dies and welding machine. The finished shell is everywhere integral, and is, as abundant Government tests have shown, everywhere 30 uniformly strong.

In the accompanying drawings—

Figure 1 shows the blank of sheet metal from which a section of the shell is produced. Fig. 2 shows the section cut from 35 said blank, the final configuration of the finished section being here developed in a plane. Fig. 3 shows said section after pressing in dies to give it the shape of a longitudinally divided half of the projectile. Fig. 4 shows said section after swaging to 40 true its shape. Fig. 5 shows two of said sections disposed in the welding electrodes.

Similar letters of reference indicate like parts.

45 In carrying out our process, we proceed as follows:

From a sheet of thin metal, Fig. 1, of suitable area we produce, by stamping, a blank, Fig. 2, which shows a configuration obtained by developing in a plane the conformation 50 of one of the two interchangeable longitudinal sections which together make up the projectile shell. This blank is then placed between suitable dies and caused by pressure to assume the concave form shown in Fig. 3. 55 If this first shaping should leave the longitudinal edges A of the section somewhat irregular and the curvature of the section not accurately true, we subject the section to a second pressing or swaging in suitable 60 dies, whereby the shape is trued and the longitudinal edges A rendered flat and smooth, as shown in Fig. 4.

We thus produce any desired number of similar and interchangeable sections, two of 65 which, B, B, Fig. 5, are seated in correspondingly recessed electrodes C, D, the edges of said sections being in registering contact, and we press said edges together while establishing the welding current. We 70 preferably employ a current of very great strength—from 5000 to 30,000 amperes per square inch—and for a very brief period of time, by which means we unite the two sections integrally, so that substantially no 75 joint appears, thus completing the projectile shell.

We claim:

As a new article of manufacture and sale, an elongated hollow projectile shell of sheet 80 metal formed integrally of two interchangeable longitudinally divided sections electrically united at their registering edges.

In testimony whereof we have affixed our signatures in presence of two witnesses.

THOMAS E. MURRAY, JR.
JOSEPH B. MURRAY.

Witnesses:

GERTRUDE T. PORTER,
MAY T. McGARRY.
